THOMAS SCOTT WILLIAMS AND FREEMAN AUGUSTUS TABER, OF BOSTON,
MASSACHUSETTS.

Letters Patent No. 105,020, dated July 5, 1870.

IMPROVEMENT IN CANDLE-LAMPS.

The Schedule referred to in these Letters Patent and making part of the same.

To all to whom these presents shall come:

Be it known that we, THOMAS SCOTT WILLIAMS and FREEMAN AUGUSTUS TABER, of Boston, in the county of Suffolk and Commonwealth of Massachusetts, have made an invention of a new and useful Improvement in Lamps, or devices for burning candles; and do hereby declare the following to be a full, clear, and exact description thereof, due reference being had to the accompanying drawing making part of this specification, and in which—

Figure 1 is a vertical section; and

Figure 2 an under-side view of a portion of a lamp for burning candles, containing our invention or improvement.

This invention is an improvement in a class of lamps or burners in which a candle is forced up to and against a cap or cover, over which is placed a deflector or "cone," as it is universally termed, when applied to kerosene-lamps.

This invention relates to means for protecting or insulating a candle from direct radiation of heat from the inflamed wick of the same, as well as to prevent the flame from creeping downward into or upon the cap or cover of the candle, the object of such protection being to prevent the melting or softening of a considerable portion of the candle by the said flame, which superfluous softening or liquefaction, it is hardly necessary to say, seriously interferes with the proper combination of the candle, as it floods its wick, clogs and disfigures the working parts of the lamp, and is objectionable in many respects.

The invention consists in interposing between the upper part of a candle and the main portion of its flame, or the upper portion of the deflector or cone surrounding such flame, and directly over the orifice of the candle-surmouinting cap, a slotted plate or shield, which, while interfering in nowise with the perfect combustion of the candle, shall, nevertheless, insulate it to a great extent from the direct radiation of heat from the flame of the wick, prevent downward passage of the flame, and retard and arrest, in a corresponding proportion, the melting or softening of the candle, which would interfere with the successful operation of candles of this class.

The drawing accompanying this specification exhibits at *a* the metallic deflector or cone; at *b*, the cap or inverted cup, which receives the upper end of the candle, such portion of the candle being represented in the drawing at *c*, and a portion of the outer case or

shell of the lamp or burner at *d*, such elements constituting part of a device for burning candles, and being arranged in proper order.

Within the upper part of the deflector *a*, and immediately below its flame-orifice or apex *e*, we dispose and affix a metallic plate or bar, *f*, which extends across the said burner, and has an orifice, *g*, formed centrally in it, to coincide with that of the apex *e*, though preferably of somewhat less area.

Heat radiated downward from the flame of the wick will be spent, to a considerable extent, upon the shield *f*, and the flame itself be cut off, and divert both from contact with the candle, thus greatly retarding the melting or softening of the body of the latter.

We have made sufficiently extended experiments to prove the correctness of our theory with regard to the shield *f*, and the fact that much less difficulty is experienced in the use of the lamp provided with it, from stoppage of the working parts from softened or melted paraffine, as is now frequently the case.

A considerable economy in waste of material is also effected by the use of our present invention, as little, if any, more is softened than is sufficient to feed the wick.

We are aware that a slotted plate has been used before in a burner for oil-lamps, to prevent the heat from passing down through the wick-tube to the oil reservoir, but our invention differs from this, in that the slotted plate is not combined with a wick-tube, but with the cone or deflector *a*, and the cap *b*, which receives the upper end of the candle. It is intended to prevent the flame creeping down through the orifice in the cap *b* into the candle, and is so shaped as to cover that portion of the top of the candle exposed by the orifice in the cap, so that the combined action of the cap and the plate is to shield the candle from the direct action of the heat of the flame.

What we claim, therefore, and desire to secure by Letters Patent, is—

In a candle-lamp, the combination with the deflector or cone *a*, and candle-cap *b* of the slotted plate or shield *f*, interposed between said parts, substantially in the manner and for the purposes set forth.

THOMAS SCOTT WILLIAMS.
FREEMAN AUGUSTUS TABER.
